UNITED STATES PATENT OFFICE.

HAROLD K. PARSONS, OF SOUTHBRIIDGE, MASSACHUSETTS.

EYE-PROTECTOR.

1,269,498.

Specification of Letters Patent. Patented June 11, 1918.

Application filed March 12, 1917. Serial No. 154,306.

To all whom it may concern:

Be it known that I, HAROLD K. PARSONS, a citizen of the United States, residing at Southbridge, in the county of Worcester and 5 State of Massachusetts, have invented certain new and useful Improvements in Eye-Protectors, of which the following is a specification.

This invention relates to improvements in 10 eye protectors and has particular reference to an improved protector especially adapted for use in the industries in those places where the user is subjected to considerable heat.

15 One of the leading objects of the present invention is the provision of a construction of this character in which the employment of metal is reduced to a minimum, and in which all metallic parts are disposed entirely on the outside of the protector.

20 A further object of the present invention is the provision of a construction of this nature which shall be extremely simple in construction, shall employ a minimum number of parts, and shall permit of the ready removal and replacement of the lenses as desired.

25 Other objects and advantages of my improved construction should be readily apparent by reference to the following specification taken in connection with the accompanying drawings, and it will be understood that I may make any modifications in the specific details of construction shown and 30 described within the scope of the appended claims without departing from or exceeding the spirit of my invention.

35 Figure I represents a front view of my complete protector.

40 Fig. II is a detailed transverse sectional view taken through one of the eye cups.

Fig. III represents a front view of a slightly modified construction.

45 Fig. IV represents a rear view of the lens frame for coöperation therewith.

Fig. V represents a plan view of the construction illustrated in Fig. III.

Fig. VI represents a sectional view of a modified construction.

50 Fig. VII represents a detail view of a further modification.

Fig. VIII represents a front view of a construction embodying the parts illustrated in Fig. VII.

Fig. IX represents a sectional view illustrating the use of said parts.

In the drawings, in which similar characters of reference are employed to denote corresponding parts throughout the several views, the numeral 1 designates the face engaging portion of my improved protector, which is preferably in the form of a molded fiber or light non-metallic and relatively non-conducting material, having pressed up therefrom the eye cups 2 terminating in the 60 form illustrated in Fig. I, in the outwardly directed flanges 3, against which rest the protecting lenses 4, locked in engagement with the flanges 3, as by the channel rims 5 encircling the lens and flange, and retained 65 in position therearound as by the end piece 6, which may be of any well known form, either screw, quick detachable clip or the like as desired.

70 My protectors may, if desired, in addition be provided with the molded inner edges providing the nose bearing pads or guards 7, and are preferably connected by a suitable pliable bridge member 8, although it will be understood that different forms of 75 bridge members may be employed if desired, or that the entire goggle may be formed in one piece in place of two separate parts, in either event head bands 9 being preferably employed to retain the same in position on 80 the face of the wearer.

85 In Figs. III to VI inclusive, I have illustrated a slightly different form of my invention, in which the flange 3 in place of being continuous, as is intended in connection with Figs. I and II, has formed therein the recesses 10, through which may pass the clips 11 on the frame 12, the flange being 90 preferably in addition provided adjacent the recesses 10 with the inclined rear face 13, terminating in the reversely sloping face 14 and stop or abutment 15. The purpose 95 of this should be at once understood, and it will be seen that in assembling this form of my protector the lens is placed within the 100 frame 12, as by placing inside certain of the clips and snapping by the remainder thereof, and the clips 11 are then placed rearwardly through the recesses 10 and the rim and flange given a relative rotative movement, whereby the clips 11 are swung slightly inward by the inclined surface 13 until they 105 pass over the apex 16, when they are se-

curely locked on the portion 14, their movement in one direction being limited by the stop 15, and the other by the apex 16, tending to lock the rim securely in place under a slight spring pressure or tension on the clip fingers 11, and at the same time permitting of ready removal of the rim and lenses as desired by reverse twisting or unlocking of the parts.

10 It is to be noted that I have illustrated as employed in connection with this construction the interposed resilient ring 17 placed between the lens 4 and the flange 3, thus insuring an air and dust tight union between these parts, and at the same time being capable of yielding as the clips are placed into position, and having a slight yielding or cushioning effect in case of a blow or the like on the lens, tending to retard or prevent 20 breakage thereof.

15 In Figs. VII, VIII and IX, I have illustrated another slight modification of my construction, in which I make use of the ring 18 adapted to encircle the eye cup 2 immediately rearwardly of the flange 3, as shown in Fig. IX, this ring bearing thereon a plurality of clips 19, certain of which may be fixed, if desired, and at least one of which is movable, as indicated in the dotted lines Fig. 25 VIII. These clips preferably have a general channel formation for embracing the flange and lens, and in addition may be provided with the rearward extension 20 to prevent any pivotal movement of the clip about the ring 18. In the use of this form of my construction the movable clip is slid around on the ring 18 to suitable position, such as indicated in dotted lines Fig. VIII, and the member 17 and lens 4 are slid in from the 30 side into correct position on the face of the flange and beneath the fixed or immovable clips 19. After the clips have been placed in position the movable clip is given a sufficient movement circumferentially of the ring 18 35 to securely and satisfactorily engage and lock the lens against any loosening movement.

40 From the foregoing description taken in connection with the accompanying drawings, the construction and advantages of my improved protector should be at once apparent, and it will be seen that I have provided 45

an extremely simple and desirable construction, in which all metal parts are reduced to a minimum and the metal parts employed 55 are all disposed exteriorly of the protector and at a point away from the face so that no disagreeable effects can occur from heating of said parts, while at the same time I am able to very simply assemble or connect the 60 parts without expensive threading operations or the like and am at the same time able to removably retain in position the lenses of the protector and facilitate their replacement as desired. 65

I claim:

1. In an eye protector, the combination with an eye cup terminating in a peripheral flange, said flange having a plurality of notches formed therein with rearwardly and forwardly inclining portions adjacent the notches on one side, of lenses, and lens retaining rims having fingers adapted to pass through the notches and be interlocked with the rims by relative rotation of the parts, 70 causing the fingers to ride upward on the inwardly inclining surfaces and finally engage the outwardly inclining surfaces. 75

2. In an eye protector, the combination with an eye cup terminating in a peripheral flange, said flange having a plurality of notches therein and inclined walls adjacent the notches, of lenses and lens rims having fingers adapted to pass through the notches and be interlocked with the inclined portions 80 by relative rotation of the parts to detachably connect the lens rims with the flange. 85

3. In a device of the character described, the combination with a mask having a bridging eye cup terminating in a channel flange, 90 of a lens adapted to fit against the flange and a retaining rim for the lens having fingers thereon adapted to be inserted through the channels in the flange and brought into interlocking engagement with the flange by 95 relative rotation of the rim and flange to securely retain the same in position.

In testimony whereof I affix my signature in the presence of two witnesses.

HAROLD K. PARSONS.

Witnesses:

EDITH M. HALVORSEN,
JOSEPH MACCARTHY.
